UNITED STATES PATENT OFFICE.

FREDERIC E. KIP, OF MONTCLAIR, NEW JERSEY, ASSIGNOR TO THE SALT'S TEXTILE MANUFACTURING COMPANY, OF BRIDGEPORT, CONNECTICUT, A CORPORATION OF CONNECTICUT.

ELECTRICAL FEELER DEVICE.

Application filed April 25, 1923. Serial No. 634,515.

To all whom it may concern:

Be it known that I, FREDERIC E. KIP, a citizen of the United States, residing at Montclair, in the county of Essex, State of New Jersey, have invented certain new and useful Improvements in Electrical Feeler Devices, of which the following is a specification.

This invention relates to electrical detector-devices or feeler-motions for controlling the operation of a loom in accordance with the condition of the weft or filling in the shuttle.

The improved feeler-device is adapted for use with both single- and double-shuttle looms, for arresting the operation of the loom when the filling in the shuttle is substantially exhausted; and also for automatic looms, to initiate the operation of the weft-replenishing mechanism which presents a fresh supply of filling to the weaving when required.

One object of the invention is to provide an electrical feeler-device in which a normally-open circuit for the loom-controlling mechanism is closed by the contact of the feeler terminals with a metal part within the shuttle.

A particular object of the invention is to provide a device in which the points of contact of the feeler on the bobbin are confined within a restricted area so that the gap between the electrical terminals or contacts is reduced to an absolute minimum, whereby to insure a more positive and effective contact of the terminals with the conductor-element in the shuttle.

Another object of the improvement is to provide a feeler-device in which the feeler, while having only a light delicate contact with the yarn on the bobbin, will still act with precision and promptness to detect the exhaustion of the filling and to close the electrical circuit for the controlling-mechanism without permitting "mispicks" or other irregularities in the operation of the loom.

Another object of the improvement is to provide a feeler-device which is simple in structure and economical to manufacture while occupying a minimum of space on the loom.

Another object of the invention is to pro-

vide a feeler-device which is adapted for practically all types of looms, and which may be applied thereto as a fitment or attachment without alteration in the structure or arrangement of the loom-mechanism.

Further objects of the improvement are set forth in the following specification which describes several preferred embodiments of the invention as illustrated in the accompanying drawings. In the drawings:

Fig. 1 is a side elevation of a usual type of single-shuttle loom showing the general arrangement of my improved feeler-device as applied to use thereon;

Fig. 2, a plan view of the feeler showing its relation to the shuttle and the bobbin carried thereby;

Fig. 3, a side elevation of the feeler-device illustrating two feelers as adapted for use with a double-shuttle loom, the shuttles and feeler-bearings being shown in cross section taken in a vertical plane on the line 3—3 of Fig. 2;

Fig. 4, a sectional view of one type of metal filling-carrier or bobbin for use with the device;

Fig. 5, a similar view of a filling-carrier having a metal sleeve on its butt;

Fig. 6, a plan view showing a preferred construction of the feeler proper which is illustrated in section on its longitudinal axis;

Fig. 7, a view of another type of feeler-mounting showing it in part section on the line 7—7 of Fig. 8;

Fig. 8, a plan view of the same showing the feeler in section on its longitudinal axis;

Fig. 9, a side view of the mounting for another type of feeler, showing it in section on the line 9—9 of Fig. 10;

Fig. 10, a plan view of the same showing the feeler in section on its longitudinal axis;

Fig. 11, a plan view of still another construction of feeler and mounting;

Fig. 12, a similar view showing a slight variation in the arrangement of the feeler-contacts;

Fig. 13, a plan view showing the feeler-elements insulated from each other by means of a hardened dielectric coating on one of them;

Fig. 14, a plan view of a portion of an au-

tomatic loom showing my improved feeler-device as applied to use with the filling-replenishing mechanism thereof;

Fig. 15, an end view of the bobbin-magazine and transerrer-mechanism of the automatic loom; and

Fig. 16, a detailed view of the electrically operated trip-device controlled from the feeler to initiate the operation of the filling-replenishing mechanism of the loom.

Referring first to Fig. 1 of the drawings, the single-shuttle plain loom therein shown is of usual structure and only the essential elements of its mechanism will be described. The frame of the loom is designated F, L indicates the lay, C the crank-shaft which reciprocates the lay, and S the shuttle which carries the filling or weft.

The power-operated driving-mechanism of the loom, not illustrated, is controlled by means of the usual shipper-lever D, normally held in operative position by a latch or detent, not shown, and adapted to be released therefrom, to arrest the operation of the loom, by means of a pivoted knock-off lever K.

Below the crank-shaft C of the loom is a cam-shaft E carrying a cam G for oscillating the rockable weft-hammer H. The weft-hammer H is pivoted on a horizontal shaft I and provided with an extension or arm H' reaching upwardly above the front of the frame F. At the inner end of the arm H' is a catch or hook h adapted to engage with the outer hooked end of a rockable latch 2. The latch 2 is pivoted on a rod or shaft 3 mounted in bearings 4 rising from the top of the knock-off lever K. Depending from the inner end of the latch 2 is a two-part adjustable link 5 which is connected to a pivoted lever 6 constituting the rockable armature of an electrical magnet 7. The magnet 7 is housed in a box 8 having a slot in its forward side in which the armature 6 is pivoted at 9. The magnet is connected in circuit with a suitable source of current and with the electrical feeler or detector-device 10, forming the subject matter of the present invention, by a system of wiring to be later described. As shown in Fig. 1, the feeler 10 is mounted at the front of the loom frame F above the knock-off lever K in position to adapt its end to enter the side of the shuttle S to "feel" or detect the condition of the filling on the bobbin carried thereby.

Reference will now be had to Figs. 2 and 6 which show one preferred form of my improved feeler and illustrate the structure of its parts and mounting in detail. In general, the feeler 10 is of the "two-pole" type comprising slidable terminals adapted to contact at two points on a metal part within the shuttle to close the circuit to the controlling-magnet 7. Conveniently, I may

employ a metal filling-carrier 11, such as illustrated in Fig. 4 of the drawings, for the circuit-closing element; while in other cases, the usual wooden bobbin or filling-carrier 12 may be fitted with a metal part or sleeve 14 on its butt, as illustrated in Fig. 5; or any other suitable electrical conductor may be arranged within the shuttle to be exposed upon the substantial exhaustion of the filling, whereby the feeler-terminals will contact therewith to close the electrical circuit. One particular object of the present improvement is to provide a two-pole feeler in which the terminals will have a minimum space or gap between their contact points and with this end in view I preferably construct the feeler of telescopic form as illustrated most clearly in Fig. 6.

As here shown the feeler 10 comprises a cylindrical-metal shell or tube 15 which is slidable in suitable bearings 16 at the ends of a rectangular frame 17. The frame 17 may be constructed of fiber or other suitable insulating-material and is provided with a threaded bolt 18 projecting from its side which is adapted to be inserted through a slot 19 in a suitable arm or bracket 20 attached to the loom frame F, see Fig. 2. Nuts 21 on the bolt 18 are tightened against washers 22 on the opposite sides of the arm 20 to secure the frame in place, and by loosening the nuts the frame may be adjusted at the proper height to locate the feeler 10 in position for its end to enter through an opening s in the side of the shuttle S to impinge upon the bobbin B carried therein. For double-shuttle looms two feelers are employed, as shown in Fig. 3, with one placed above the other on the arm or bracket 20, whereby they are adapted to enter both shuttles S to effect the control of the loom in accordance with the condition of the filling in either shuttle.

As before stated, the outer feeler-element or tubular terminal 15 is slidable in its bearings in the frame 17, and arranged to telescope within the tube is a second slidable contact-element in the form of a rod or plunger 25, see Fig. 6. The plunger 25 slides in the axial bore of a sleeve 26 which is constructed of fiber or other suitable dielectric material and fitted within the tube 15 to provide an insulating medium between the two contact-elements or terminals of the electrical circuit to be later described. At the right-hand end of the feeler 10 the bore of the sleeve 26 is enlarged at 27 to adapt it to receive a coiled wire spring 28 which bears against an enlarged head 30 on the end of the plunger 25. A screw 31 threaded into the end of the enlarged bore 27 of the sleeve 26 acts as a stop for the spring 28, the screw being adjustable in the bore to vary the tension of the spring and carrying a check-nut 32 for locking the adjustment. Surround-

ing the outer tube or shell 15 is a second helical spring 33 bearing at one end against a collar 34 fastened to the tube by a set-screw 35, see Fig. 2, and at its opposite end against 5 the cross-bar 36 of the frame 17. The spring 33 maintains the tube 15 in the position shown in Figs. 2 and 6 with the collar 34 bearing against the cross-bar 37 of the frame 17, and by altering the position of the collar 10 on the tube the complete feeler 10 may be adjusted longitudinally in the frame to regulate its position with respect to the bobbin B on which its end impinges, see Fig. 2. It will be noted that the inner contact-element 15 or plunger 25 is so proportioned that when 15 its head seats against the end of the enlarged bore 27 in the sleeve 26 its opposite rounded end will project slightly beyond the end of the outer tube or contact-element 15. This 20 arrangement of the parts provides that the inner plunger or contact-terminal 25 will impinge first on the side of the bobbin B in the shuttle S at the beat up of the lay L, see Fig. 1, and, as the spring 28 acting against 25 said plunger is considerably lighter and weaker than the spring 33 for the tube 15, the plunger will be telescoped with respect to the tube. After the end of the plunger 25 has been telescoped within the tube 15, how- 30 ever, the end of the tube itself will be impinged upon the bobbin and as the lay continues its forward beat both contact-elements 15 and 25 are slid back as a unit against the force of the spring 33. This initial retrac- 35 tion of the plunger 25 and eventual sliding movement of the contact-elements as a whole takes place at every second beat up of the lay when the shuttle is boxed on the feeler side of the loom. Normally, the contact- 40 elements or terminals of the feeler 10 impinge upon the yarn on the filling-carrier or bobbin B in the shuttle S, but when the filling is substantially exhausted the metal part of the carrier is exposed and the ter- 45 minals of the feeler will contact therewith to close the electrical circuit which controls the operation of the loom in the manner and for the purpose as hereinafter fully explained.

Figs. 7 and 8 illustrate another embodiment 50 of the improved feeler in which the parts are arranged for more compact grouping. In this modified form of the device the rectangular supporting frame or bracket 40 is constructed of metal with a fiber strip 55 or backing 41 attached to its under side by means of screws 42. The outer tube or contact-element 45 slides in bores at the ends of the frame 40 and is reduced in diameter at one end to receive a nut 46 threaded thereon. 60 The nut 46 contacts with one of the end cross-bars of the frame 40 and is adapted for adjustment to regulate the longitudinal position of the feeler with respect to the bobbin in the shuttle, to provide for the proper contact of the feeler therewith.

Within the tube 45 is an insulating sleeve or bushing 47 having an enlarged rim or flange 48 at its end which seats against the end of the tube. The plunger-rod 50 which slides in the sleeve 47 is bent at right-angles 70 at 51, the bent portion being adapted to abut the end of the sleeve to locate the plunger with its end projecting beyond the end of the outer tube or terminal 45. An extension 52 of the rod 50 is bent back into parallel relation with the main portion of the plunger to adapt it to slide through an insulating thimble 53 inserted in a bore in the cross-bar 54 of the frame 40. At the end of the extension 52 is a collar 55 between which and the thimble 53 is a relatively light coiled spring 56. A second heavier spring 57 surrounds the outer tube 45 between its adjusting-nut 46 and the cross-bar 54 of the frame 40 and acts to resist the sliding movement of the feeler as a whole. The extension 52 of the rod 50 slides through a metal washer 59 at the end of the insulating thimble 53, the washer being connected by a wire 60 to a binding-post 61 on the insulating strip 41. The binding-post 61 is connected by wiring, not shown, to the electrical circuit for the controlling-magnet 7, previously referred to, and the outer contact-member or tube 45 is grounded in the frame of the loom through the metal frame 40 mounted thereon in the manner as previously described. In this manner both terminals of the feeler are connected with the magnet by a normally open circuit which 90 is closed by the concurrent contact of the terminals with the conductor in the shuttle. This form of device operates in substantially the same manner as that previously described, the plunger-rod 50 being adapted 100 to yield against the pressure of its light spring 56 to telescope it within the tube 45, and the whole feeler yielding as a unit against the tension of the heavier spring 57.

Another modified form of the feeler is illus- 105 trated in Figs. 9 and 10 in which the supporting frame 62 is of metal constructed with a central cross-bar 63. The tubular contact-element 65 slides in bearings in the cross-bars 63 and 64 of the frame 62 and 115 carries an adjusting nut 66 for regulating its normal position. Between the nut 66 and the cross-bar 63 of the frame 62 is the main compression-spring 67, and within the tube is an insulating-bushing 68 formed with an end flange 69. The inner contact-element or plunger-rod 70 slides in the sleeve 68 and also in the end cross-bar 64 of the frame 62, a fiber thimble 71 serving to insulate it from the frame. A relatively light 120 spring 72 surrounds the plunger 70 between a collar 73 abutting the end of the fiber sleeve 68 and a metal washer 74 at the end of the thimble 71. With this arrangement 125 of the parts the outer tube or contact-ele- 130

ment 65 is electrically connected with the controlling-magnet through the metal frame 62 grounded in the frame of the loom; while the plunger 70 is connected to the other side 5 of the circuit by a wire 75 extending from the washer 74 to a binding-post 76 on the fiber plate 77 attached to the frame 62. It will be obvious without further explanation that the two contact-elements 65 and 70 in 10 this form of device are adapted to operate in the same manner as those of the arrangements first described.

Figs. 11 and 12 show a further simplified and compacted arrangement of the feeler-device which may be considered as a preferred form of the invention. In these two views the supporting frame 80 is constructed of fiber or other insulating-material with a flat base 81 and two upstanding end-pieces 83 and 84. The outer tubular contact-element 85 slides in a bore in the end-piece 83 and is provided with an end-flange 86 for locating it in position. The flange 86 abuts a plate 87 attached to the end-piece 83 by a screw 88 which is provided with nuts 89 whereby to adapt it to serve as a binding-post. The tube 85 slides through a hole in the plate 87 and is thus electrically connected to the plate at all times, the plate, in turn, 30 being grounded in the loom frame by means of a wire 93 leading from the binding-post 88. Fitted to the interior of the tube 85 is an insulating-sleeve 94 within which the plunger-rod 90 slides. The right-hand end 35 of the plunger 90 slides in a bore in the end-piece 84 of the frame 80 and also through a hole in a metal plate 96 attached to the end-piece by a binding-screw 97. The binding-post 97 is connected in the magnet circuit by a wire 98. On the rod 90 is a split collar 99 clamped thereto by a screw 100. A coiled spring 101, encircling the rod 90 between the collar 99 and plate 96, acts to resist the sliding movement of the plunger; 40 while a second shorter spring 102 is arranged between the collar 99 and a fiber washer 104 abutting the flanged end of the tube 85. The fiber washer 104 separates the spring 102 from the tube 85 so that the two contact-elements 85 and 90 are completely insulated from each other while being individually connected in circuit with the electrical control-mechanism through their respective binding-posts previously referred to. With 45 this last-described arrangement as illustrated in Fig. 11 the springs 101 and 102 maintain the two terminals or contact-elements in the relation illustrated in Fig. 11 with the plunger 90 projecting beyond the end of the tube 85. The impingement of the plunger on the bobbin in the shuttle causes it to be telescoped within the tube 85 against the pressure of the spring 101, and finally the tube itself will be slid back or retracted 50 against the force of this spring. With this

arrangement the second spring 102 acts merely as a locating medium for the tube 85 and only the single spring 101 resists the sliding action of the feeler. It will be observed therefore that the resistance to the 70 action of the feeler may be reduced to a minimum so that its contact with the bobbin is very light and delicate, thus removing any danger of injury to the yarn.

As before mentioned, Fig. 12 shows substantially the same structure of the feeler-device as in Fig. 11, but it is to be noted that the adjustment of the parts of the device is varied slightly. That is to say, in Fig. 12 the collar 99 on the plunger 90 is 75 adjusted in such position longitudinally thereof that normally the outer contact-element or tube 85 projects beyond the telescoped plunger 90. This variation in the arrangement provides that the tube 85 will 80 impinge first upon the bobbin, and sliding against the force of its spring 101 will eventually provide for the impingement of the plunger 90, whereupon both elements 85 will yield together as a unit. Either of the 90 last described arrangements may be employed as preferred and the action of the feeler is essentially the same as before explained.

In Fig. 13 a slight modification in the 95 structure of the cooperating contact-elements is illustrated. In this embodiment of the invention the inner terminal or plunger 105 is insulated from the tube 106 by a coating of hardened dielectric material on its surface. That is to say, the plunger may be covered with a coating 107 of vulcanized rubber, bakelite or baked enamel which serves as the insulating medium between the parts without requiring an inner sleeve for the 100 tubular contact-element. With this arrangement the contact-end of the plunger 105 is of course left bare, and preferably it is reduced in diameter to insure against electrical contact with the tube 106 when the parts are 110 in telescoped relation. By employing this method of construction the tubular terminal 105 may be made much smaller in diameter and the proportions of all of the other parts of the device reduced to an absolute minimum. 115

It has been stated that the present improved feeler-device is adapted for use in connection with any usual form of electrically-operated stop-motion for the loom and the manner of connecting it in circuit therewith is illustrated more or less diagrammatically in Fig. 1 of the drawings. In this view the tubular terminal 15 of the feeler is connected to a wire 110 grounded at 111 in the loom frame F; while the inner plunger or terminal 25 has a wire 115 leading to a battery 116 or other source of current which, in turn, is connected by a wire 117 to the magnet 7. The opposite lead wire 118 from the magnet 7 is grounded 120 125 130

in the loom frame F at 119 and in this way both sides of the circuit are connected to the terminals of the feeler. As the lay L is oscillated during the operation of weaving 5 the fabric the shuttle S is boxed on the feeler side of the loom at each alternate pick thereof. Therefore, at every alternate beat up of the lay the feeler 10 will be caused to enter the opening s in the side of 10 the shuttle, see Fig. 2, to impinge upon the side of the bobbin B. Under this action the feeler will be forced back by first telescoping its plunger 25 and then sliding its tube 15 and as long as a covering of yarn re- 15 mains on the butt of the bobbin the terminals of the feeler will be prevented from contacting with the metal part of the filling-carrier so that no electrical connection is made between the poles of the feeler. When, 20 however, the yarn is finally unwound from the butt of the bobbin the metal part of the filling-carrier is exposed and the ends of the plunger 25 and tube 15 will both contact with the conductor under the tele- 25 scopic action of the feeler so that the circuit is closed across the terminals. It will be understood, of course, that the bobbin B is wound with a short length of filling, called the "bunch winding," indicated at b in Figs. 30 2 and 4, before the service winding is started, so that the bunch will still remain to be unwound after the yarn on the butt of the filling-carrier has been unreeled. This pro- 35 vides that a sufficient length of yarn will remain on the bobbin to make a complete pick in the fabric when the shuttle is thrown across the loom after the service winding is exhausted and before the feeler has had an opportunity to function. 40 When the electrical circuit is closed across the terminals of the feeler, in the manner as above explained, the magnet 7 will be energized by the current from the generator or battery 116 and will therefore attract its 45 armature 6 to rock it on its pivot 9. The rocking movement of the armature 6 acts through the rod 5 to tilt the latch-lever 2 to depress its catch into range of the hook h on the arm H' of the weft-hammer H. It 50 has been explained that the weft-hammer H is oscillated from the cam G and it is to be noted that the cam-shaft E is driven from the crank-shaft C by gears e and e which have a ratio of 1 to 2. This provides 55 that the crank-shaft makes two revolutions to one for the cam-shaft so that the weft-hammer is oscillated only at every alternate beat up of the lay. The operation of the cam G is timed to rock the weft-hammer H to draw its hook h forward during the 60 dwell of the lay at the end of its beat up so that as the terminals of the feeler close the circuit and energize the magnet to trip the latch 2 the hook h will be carried forward 65 to engage with the latch. Immediately this engagement takes place the latch 2 is drawn forward by the hook h to swing the knock-off lever K on its pivot to force it against the shipper-lever D, whereby to release the latter from its detent. The release of the 70 shipper-lever D allows it to spring back to shift the driving-belt, release the clutch, or shut off the power from the loom in any suitable manner as well known to those versed in the art. In this way the stopping 75 of the loom is effected with the required promptness and always at a definite point in the weaving operation when the shuttle is boxed on the side where the weaver stands. 80 The improved feeler may be applied to use in connection with automatic looms to initiate the operation of the filling-replenishing mechanism by connecting it in circuit with an electrical means for controlling said mechanism. Figs. 14, 15 and 16 illustrate 85 a well-known arrangement of filling-changing mechanism such as used on Draper looms, but it will be obvious that the present invention is adaptable for use with other types of such devices employed for the same purpose. 90 Fig. 14 is a plan view of that portion of the automatic loom on which the feeler-device may be conveniently mounted, L designating the lay, S the shuttle and N the breast-beam 95 at the front of the loom frame F. The supporting frame 17 for the feeler 10 is mounted on its bracket 20 fastened to the top of the breast-beam N and is adjustable in position, as previously explained, to adapt the end of the feeler to enter the opening s in the 100 shuttle S to feel the condition of the filling on the bobbin B. The tubular terminal 15 of the feeler is grounded in the loom frame F at 125 while the plunger terminal 25 is connected by a wire 126 to a battery 127. 105 from which a conductor 128 leads to a pair of magnets 130. The magnets 130 are supported on an elbow-shaped arm 131 fastened to the top of the breast-beam N, and the opposite side of their circuit comprises a wire 110 132 which is grounded in the loom frame at 133. 115 On the top of the breast-beam N is a slide 134 carrying a pivoted armature-lever 135 having its shorter weighted arm 136 normally held by gravity in depressed relation to the magnets 130. The lever 135 is pivoted across the forked end of the slide 134 and its shorter arm 136 is weighted to normally hold its longer arm in raised position 120 above the end 137 of the vibrating weft-hammer 138. Referring to Fig. 14, the longer arm of the lever 135 is formed with a slot 139 with which the end 137 of the weft-hammer 138 engages when the shorter arm is 125 lifted by the attraction of the magnets 130. When the armature-lever 135 is thus engaged with the weft-hammer 138 the forward movement of the latter will slide the slide 134 forward to engage it with an arm 130

140 on a rock-shaft 141 journaled in bearing 142 at the front of the breast-beam N. The rock-shaft 141 carries an elbow-shaped lever 143 at its opposite end which operates 5 the trip-device for the filling-replenishing mechanism on the magazine side of the loom, see Figs. 15 and 16.

Referring to Fig. 15, 150 designates the usual rotatable hopper or magazine which 10 carries the reserve supply of filling-bobbins B on its rim. The transerrer 151 which transfers the bobbins from the hopper to the shuttle is pivoted at 152 and provided with an operating-arm 153 carrying the dog 154 15 at its lower end. The dog 154 is connected to an elbow-shaped arm 155 by means of a pin 156 engaging an angular slot 157 at the end thereof. The arm 155 is pivoted at 158 and is operated from a member 159 suspended from the lever 143 on the rock-shaft 141, whereby to raise the dog 154 into position to be engaged by a bunter 160 on the lay L. The member 159 is provided with a leg 161 having a beveled end 162 which 25 normally engages with a pin 163 on the elbow of the arm 155. A spring 165 hooked to the end of another leg 166 on the member 159 is anchored to a fixed part of the loom at 164 and acts to rock the member 159 to 30 swing the arm 155 in the manner and for the purpose as later explained. These last mentioned elements of the filling-changing mechanism are of usual construction and arrangement and therefore require no further 35 detailed description.

The method of operation of the feeler-device in connection with the filling-changing mechanism is as follows: When the filling on the bobbin in the running shuttle is 40 substantially exhausted and the conductor on the butt of the filling-carrier is exposed, so that the ends of the plunger 25 and tube 15 impinge thereagainst to close the circuit across the feeler terminals, the magnets 130 will be energized by the current from the battery 127. The magnets will therefore lift the shorter arm 136 of the armature-lever 135 to rock its longer slotted arm into position to be engaged by the end 137 of the 45 weft-hammer 138, as illustrated by dotted lines in Fig. 16. This action causes the slide 134 to be locked to the weft-hammer 138 so that as the latter moves forward it will push the slide forward to rock the arm 140 in the 50 direction indicated by the arrow α in Fig. 16. This movement of the arm 140 turns the rock-shaft 141 to raise the lever 143, see Fig. 15, whereby the beveled end 162 of the leg 161 on the member 159 is released from the pin 163 on the arm 155; whereupon the spring 165 will tilt the member 159 to raise 55 its leg 161 and thereby rock the arm 155 upwardly. This upward movement of the arm 155 acts through the pin and slot connection at 156, 157 to lift the dog 154 into

position to be engaged by the bunter 160 on the lay L as the latter moves forward at the next beat up; it being understood that the last-described motions of the trip-device take place as the lay is moving back after 70 the feeler 10 has closed the electrical circuit to the controlling magnets 130. Now, after the shuttle S makes another pick across the loom and is boxed on the magazine side 75 thereof the lay moves forward again and its bunter 160 strikes the notched end of the dog 154 to rock the arm 153 to depress the transerrer 151. Through this action the transerrer 151 is caused to transfer a fresh 80 bobbin from the magazine 150 to the shuttle S and the spent bobbin is ejected therefrom in the usual manner well known to those versed in the art. In this manner the filling-feeler or detector acts promptly and efficiently to initiate the operation of the 85 filling-changing mechanism so that a fresh supply of filling will invariably be inserted in the shuttle before the yarn is entirely exhausted from the running bobbin, the bunch winding on the filling-carrier providing sufficient yarn for the last pick before 90 the bobbin is changed.

By arranging the contact-elements of the feeler with one projecting in advance of the other so that it impinges first upon the bobbin and is retracted with respect to the other element until both elements are moved as a unit, a surer and more positive electrical contact of the terminals on the conductor is insured. Moreover, this peculiar arrangement of the contact-elements provides that they will both engage positively with the irregular, tapered butt of the bobbin, or with any other conductor thereon, notwithstanding that its surface may be grooved, 100 corrugated or otherwise roughened.

I am aware that it is old in the art to provide a two-pole electrical feeler having yieldable contact-elements adapted to impinge upon the bobbin in the shuttle and to contact with a conductor exposed by the substantial exhaustion of the filling, whereby to close the circuit which controls the operation of the loom. I believe, however, that I am the first to devise a feeler of this type in which both the contact-elements are combined in a unitary structure with their contact points disposed in overlapping relation to confine them to a restricted area of contact, so that the gap between the terminals is reduced to a minimum to insure a more positive and efficient contact of the elements with the conductor. I therefore claim this combination broadly without limitation as to the details of construction of 115 the parts of the device.

I claim:

1. An electrical feeler comprising a pair of yieldable contact-elements having their contact-points arranged in axial alinement 120

- to confine them to a restricted area of contact on the bobbin, means to insulate said contact-elements from each other, and means to adapt the contact-elements to yield singly or as a unit. 5
2. An electrical feeler comprising a pair of yieldable contact-elements, one of said elements having its contact-end enclosing the contact-end of the other element, and 10 means to adapt said elements to yield, one with respect to the other and both together as a unit, when impinged upon the bobbin in the shuttle. 15
3. An electrical feeler comprising a pair of yieldable contact-elements having their contact-points arranged in axial alinement, with the contact-end of one element projecting in advance of that of the other element, an insulating medium separating said elements, and means to adapt said elements to yield either singly or as a unit when impinged upon the bobbin in the shuttle. 20
4. An electrical feeler comprising a pair of interrelated contact-elements arranged in axial alinement to slide independently of each other longitudinally of their common axis or together as a unit, an insulating medium separating said elements, and resilient means for maintaining said elements in position to enter the loom shuttle with one element in advance of the other element whereby it impinges first on the bobbin and is retracted with respect to the other element. 25
5. An electrical feeler-device for looms 30 consisting in a two-pole yielding feeler adapted to enter the shuttle to feel the condition of the filling carried thereby, said feeler comprising in a unitary structure a plurality of contact-elements arranged in axial alinement and adapted for relative sliding movement longitudinally of their common axis and also for yielding action as a whole, said contact-elements acting to close an electrical circuit when concurrently impinged upon a conductor-element in the shuttle. 35
6. In a feeler-device, the combination with the electrical controlling-mechanism of a loom, of a unitary feeler comprising a pair of intercontained contact-elements 40 arranged in axial alinement and adapted for individual sliding movement longitudinally of their common axis and also for yielding movement as a whole, said contact-elements connected in circuit with the electrical loom-controlling mechanism to close said circuit when both elements contact concurrently with a conductor exposed by the substantial exhaustion of the filling in the bobbin. 45
7. In a device of the type specified, a two-pole electrical feeler adapted to enter the loom shuttle to feel the condition of the filling therein, said feeler comprising in a unitary structure a plurality of telescopic contact-elements disposed with one element pro- 50
- jecting beyond the other element and adapted to be displaced relatively thereto and both elements arranged for displacement as a whole, said contact-elements adapted to close an electrical circuit when concurrently impinged upon a conductor exposed by the substantial exhaustion of the filling in the shuttle. 55
8. In a device of the type specified, a two-pole electrical feeler comprising in combination, a pair of slideable contact-elements arranged to telescope one with respect to the other, and resilient means for maintaining one of said elements longitudinally in advance of the other element while permitting both elements to yield when concurrently impinged upon the bobbin in the shuttle, whereby said elements act to close an electrical circuit by contact with a conductor exposed by the substantial exhaustion of the filling in the shuttle. 60
9. A two-pole electrical feeler for looms comprising a pair of contact-elements arranged in telescopic relation but insulated from each other, resilient means for maintaining one of said elements axially in advance of the other element while allowing said elements to be telescoped and to thereafter yield as a unit, whereby both elements may be impinged upon the bobbin in the loom shuttle to make contact with an electrical conductor at closely adjacent points thereon to close an electrical circuit for which said contact-elements form the terminals. 65
10. In combination with the controlling mechanism of a loom and an electrical circuit for operating the same, a two-pole unitary feeler in said circuit adapted to enter the loom-shuttle to feel the condition of the filling on the bobbin, said feeler comprising coaxial contact-elements arranged to slide individually and as a unit longitudinally of their common axis, one element projecting beyond the other element to adapt it to impinge first upon the bobbin, and both elements adapted to contact concurrently with a conductor exposed by the substantial exhaustion of the filling on the bobbin to close the electrical circuit. 70
11. In combination with the controlling mechanism of a loom and an electrical circuit for operating the same, a two-pole unitary feeler adapted to enter the shuttle to feel the condition of the filling on the bobbin, said feeler comprising a tubular contact-element, a second contact-element telescopically mounted within the first element, resilient means for maintaining one of said contact-elements with its end projecting beyond the end of the other element, and resilient means for maintaining the feeler in position to enter the shuttle while allowing it to yield as a whole. 75
12. A two-pole electrical-feeler for looms comprising a contact-element adapted to 80
- 85
- 90
- 95
- 100
- 105
- 110
- 115
- 120
- 125
- 130

enter the shuttle to impinge upon the bobbin and to yield longitudinally under the beat up of the lay, a second contact-element in telescopic arrangement with the first element, and resilient means for maintaining the first element with its end projecting beyond that of the second element whereby one element impinges upon the bobbin in advance of the other element and both elements are adapted to contact with a conductor in the shuttle with a minimum gap between their points of contact.

13. A two-pole electrical feeler comprising a tubular contact-element adapted to enter the shuttle to impinge upon the bobbin and to slide longitudinally under the beat up of the lay, a second contact-element in telescopic arrangement with the first element and slidable with respect thereto, resilient means for maintaining the contact-elements in position to enter the shuttle with one member in advance of the other to impinge first upon the bobbin and to be slid thereby, whereby both elements will eventually contact with a conductor on the bobbin exposed by the substantial exhaustion of the filling thereon.

14. In an electrical feeler-device for looms, the combination with a support, of a tubular contact-element slidable in bearings thereon, a second contact-element arranged in telescopic arrangement with the tubular element, a spring for maintaining

one element with its contact-end in advance of the other element, and a second spring for maintaining both elements in position to enter the loom shuttle to feel the condition of the filling therein.

15. In an electrical feeler-device for looms, the combination with a support, of a tubular contact-element slidable therein, a second plunger-element slidable in the tubular element, a spring for maintaining the contact-elements in position to enter the shuttle while permitting them to be retracted upon impingement upon the bobbin, and a second spring acting between the tubular element and the plunger to maintain the contact-end of one of said elements projected in advance of the end of the other element.

16. Loom-controlling mechanism comprising an electro-magnet and a circuit therefor adapted to be closed through a conductor in the shuttle exposed upon substantial exhaustion of the filling, and contact-elements constituting the terminals of the circuit and engageable with the conductor in the shuttle, said contact-elements so combined as to permit movement of one upon the other to enable concurrent contact of the contact-elements with the conductor at a predetermined time.

In testimony whereof I affix my signature.

FREDERIC E. KIP.
